UNITED STATES PATENT OFFICE.

FRED P. DE WILDE, OF VAN HOUTEN, NEW MEXICO.

CUFF-HOLDER.

1,111,367.

Specification of Letters Patent. Patented Sept. 22, 1914.

Application filed December 27, 1911. Serial No. 668,152.

To all whom it may concern:

Be it known that I, FRED P. DE WILDE, citizen of the United States, residing at Van Houten, in the county of Colfax and State 5 of New Mexico, have invented certain new and useful Improvements in Cuff-Holders, of which the following is a specification.

This invention relates to improvements in cuff holders, and has for one of its objects 10 to provide a simply constructed device of this character which will yield to outwardly directed strains to enable the cuff to be moved upwardly upon the shirt sleeve when washing the hands or doing work that would 15 soil the cuffs if left in their downward position, and likewise to enable the cuffs to be adjusted upon the shirt sleeve.

The primary object of the invention is to 20 provide means for holding the edges of a cuff together in the usual manner, that is, in the same manner as a link or other cuff button, the button members which are received by the button holes of the cuff being normally forced toward each other to support 25 the edges of the cuff in proper alinement, the cuff supporting member being yieldable in order that the cuff may be moved upon the forearm without being disarranged or in any way distorted.

30 A further object of the invention is to provide yielding means for normally maintaining the edges of the cuff in proper alinement, which will cause the cuff to firmly embrace the forearm at any point to which it 35 is raised, effectually holding the cuff against being accidentally lowered.

Another object of the invention is to provide 40 a device of this character which is readily adaptable to cuffs of various sizes and forms without structural change either in the cuff or the device.

With these and other objects in view, the 45 invention consists in certain novel features of construction as hereafter shown and described, and then specifically pointed out in the claims, and in the drawings illustrative of the preferred embodiment of the invention:

Figure 1 is a perspective view of a portion 50 of a shirt sleeve including the wristband and the cuff with the improvement applied; Fig. 2 is a plan view of the improved device; Fig. 3 is a section on the line 3—3 of Fig. 2; Figs. 4 and 5 are views of the two 55 main body portions of the device from the inside.

Corresponding and like parts are referred to in the following description and indicated in all the views of the drawings by the same reference characters.

The improved device comprises a body 60 formed of hollow casing or shell members 10—11 with inwardly directed rims 12—13 engaging face to face, and with central openings surrounded by inwardly directed 65 flanges 14—15, which also engage face to face. By this means an annular shell-like structure is produced.

Extending through the opening produced 70 by the flanges 14—15 is a locking sleeve 16 having a flange 17 at one end and a transverse bar or plate 18 at the other end, the bar and the flange serving to lock the sleeve 16 in the shells and likewise to connect the 75 shells and prevent their movement away from each other, but providing means whereby the two shells may be freely rotated upon the sleeve as a center. The plate 18 is bent into elongated U-form as shown, and with a resilient tongue 19 connected to the outer 80 member of the plate and bears yieldably upon the inner member of the plate as shown in Fig. 3. The free end of the tongue 19 is bent outwardly and extends through an aperture in the outer member of the plate 18. 85 Pivoted at 20 to the outer member of the plate 18 is a cam lever 21 which operates against the tongue 19 and compresses the latter inwardly toward the shells. By this simple means an effective spring catch device 90 is produced whereby the shells may be yieldably connected to a shirt sleeve or other garment, as hereafter explained.

Extending from the rim 12 of the half shell member 10, is a bearing 22, while a 95 similar bearing 23 extends from the rim 13 of the half shell member 11 from the opposite side. A rod 24 is supported in the bearing 22, while a similar rod 25 is supported in the bearing 23, the two rods extending at one side partly around the casing members 10—11, and are thence extended radially of the casing and in parallel relations as shown at 26—27 and thence directed 100 outwardly at their terminals as shown at 28—29, and provided with buttons or heads 30—31 at their outer ends.

Located within the shell 10—11 is a spring 105 represented as a whole at 32 and connected at one end to a pin 33 extending inwardly 110 from the shell 10 and at the other end to a pin 34 extending inwardly from the shell

11. By this arrangement the spring exerts its force to maintain the arms and their buttons yieldably in closed position, or with the arms or rods in engagement as shown 5 in Figs. 1 and 2.

The buttons 30—31 may be constructed of any suitable material and of any ornamental shape and conform in material and appearance to any of the various forms of 10 cuff buttons or cuff links in common use.

The cuff in this manner may be raised to any point along the forearm, and the arms will exert sufficient pressure on the buttons to draw the edges of the cuff toward 15 each other and snugly grasp the arm. The cuff in this way is retained against movement at any point on the forearm, its adjustment on the forearm being secured without manipulation of the device, by merely 20 drawing the sleeve upward. Thus, if the hands of the wearer should be soiled and he should desire to wash them, it is unnecessary for him to grasp the cuffs or the securing device to raise the cuffs to a position 25 where the water would not contact with the cuffs, the garment being grasped at a point which, if soiled, would not show at the wrist line when the cuffs are brought to their normal position. Particular attention 30 is called to the fact that by this construction there is no danger of the cuffs slipping downward when they have been raised, as the pressure on the cuff supporting arms is constant and so directed that 35 the cuff, and not the securing device, is forced in contact with the arm.

The improved device is simple in construction, can be inexpensively and strongly manufactured, and of any suitable material 40 and of any suitable size.

Having thus described the invention, what is claimed as new is:

1. A cuff fastener including a sectional casing, each of the sections of said casing 45 being formed with an inwardly disposed portion, a connecting member passing through said inwardly disposed portions, whereby the sections may rotate one upon the other, a pin carried by each of the sections and disposed within the casing, the pin of one section being supported adjacent its periphery and the pin of the other section being supported adjacent its center, a spiral spring, each of said pins being connected to a terminal of said spring, and

cuff engaging means supported by each of the sections of the casing.

2. A cuff fastener including a sectional casing, the sections of said casing having their central portions inwardly directed, a connection 60 between the central portions whereby the sections may rotate with respect to each other, the inwardly disposed portions forming a hub, a spring coiled about said hub, a pin carried by one of the sections and disposed adjacent its center and connected to one terminal of said spring, a pin carried by the other of said sections and disposed adjacent its periphery and connected to the other end of said spring, and a button supporting arm supported by each of the sections of the casing.

3. A cuff fastener including a pair of plates formed at their edges with inwardly directed flanges and provided centrally with inwardly directed sleeves, a member passing through the sleeves and connecting the plates, whereby they may rotate with respect to each other, a spring coiled about the sleeves 75 of the plates, said spring having one of its terminals connected to one plate and its other terminal to the other plate, each of the plates being formed with a pintle lug, an arm rotatably supported by each lug, 80 each of said arms being curved to embrace the plates, the arms extending beyond the plates and being normally maintained parallel by the action of the spring, and cuff engaging means arranged on each of said 90 arms.

4. A cuff fastener including a sectional casing, each of the sections being formed with an inwardly disposed portion, a connecting member passing through the inwardly disposed portions, whereby they may 95 rotate one upon the other, a spiral spring, means carried by one of the sections for securing the inner terminal of the spring, means carried by the other section for securing the outer terminal of the spring, and cuff engaging means carried by each section of the casing.

In testimony whereof, I affix my signature in presence of two witnesses.

FRED P. DE WILDE. [L. s.]
